UNITED STATES PATENT OFFICE.

FREDERICK M. TURCK, OF NEW YORK, N. Y., ASSIGNOR, BY MESNE ASSIGNMENTS, OF ONE-HALF TO MABEL TRACY, OF SAME PLACE.

NUMBERED MANIFOLD-BOOK.

SPECIFICATION forming part of Letters Patent No. 651,171, dated June 5, 1900.

Application filed May 27, 1899. Serial No. 718,541. (No model.)

To all whom it may concern:

Be it known that I, FREDERICK M. TURCK, a citizen of the United States, and a resident of New York, in the county of New York and State of New York, have invented certain new and useful Improvements in Numbered Manifold-Books, of which the following is a specification.

My invention relates to numbered manifolds in which loose leaves are placed into a holder or otherwise secured to the cover of a book; and the objects of my invention are, first, to simplify the process of manufacture of numbered manifold or other books; second, to facilitate the handling, and, third, to insure accuracy in the numbering, as being manufactured in one piece the books will be more reliable than would be the case if manufactured and shipped separately.

My invention will be hereinafter fully described, and specifically set forth in the annexed claims.

In the accompanying drawings, forming part of this specification, Figure 1 is a face view of the combined book. Fig. 2 is a perspective view of same, showing the top leaf turned over. Fig. 3 is a face view of a part of said book, showing the difference in construction when the same is used for duplicate copies.

In the practice of my invention a book A, with printed blanks of any desirable form, consisting, preferably, of twenty-five leaves, is bound together by staples C C or otherwise. Each leaf is divided into five spaces by means of perforations B', B², B³, and B⁴. The first portion D of the leaves of the book A has both of its sides numbered as follows: The upper face of the bottom sheet is numbered "1", the sheet on top of it is numbered "2" on its upper face, and so on, when the number "25" will appear on the top leaf, as shown in Fig. 1 of the drawings. The under face of the top sheet of portion D will be numbered "26," as shown in Fig. 2, but in an opposite or reversed position toward the number "25." The sheet underneath that will be numbered "27," and so on, when the number "50" will appear on the under face of the bottom sheet, and the said bottom sheet will be numbered "1" on one side and "50" on the other side.

The next section, embracing portions D' and D², is numbered from "1" to "25" consecutively, as shown in Fig. 2 of the drawings. It is optional whether the numbers be printed on one or both sides, the object being that each division shall have a number. The section embracing D³ and D⁴ is numbered from "26" to "50" consecutively, as shown in Fig. 2, in the same way and for the same purpose as already described.

This book is adapted to be used for duplicate and triplicate copies, is very simple to manufacture, and on account of its being made and delivered to the consumer in one piece it is much more reliable than were it made and delivered in sections.

In use the portion D is separated from the sections D' D² and D³ D⁴ on the line of perforation B' and becomes a record-book, and the other two sections D' D² and D³ D⁴ are separated from each other on the line of perforation B³, and the section numbered "1" to "25" is placed upon the section numbered "26" to "50," when the pile will be numbered from "1" to "50" consecutively. The pile of loose leaves are then placed into a holder and used in the usual manner.

The separated book used as a record-book consists of twenty-five leaves, but is attached to its holder in a reversible manner, so that both sides of the leaves can be used, thus taking but half the paper usually required.

When the book is to be used for duplicates only, the portion D need be merely wide enough to accommodate the stitches or binding and becomes a stub, which stub is numbered, however, and when separated from the leaves or sheets will serve to indicate the number of leaves that have been detached.

When the book is given out to the salesman, the stub is retained in the office and indorsed with the number or name of the salesman to whom the detached leaves have been supplied, thus becoming a safeguard and check against the salesman.

Having thus described my invention, what I claim as new, and desire to secure by Letters Patent, is—

1. A manifold memorandum-book, consisting of a pile of leaves bound together at one end, each sheet divided into five spaces by

perforations, the first section consisting of one space numbered on both sides to become a reversible book, and the other two sections each numbered consecutively from the first 5 section of the first leaf through all the first sections and then through all the second sections to the second section of the last leaf, said sections to be superposed one upon the other when separated, so that the numbers 10 will come in consecutive order, substantially as set forth.

2. A manifold memorandum-book consisting of a pile of leaves bound together at one end, each sheet divided into five spaces by 15 perforations, the first section consisting of one space numbered on both sides to become

a stub, and the other two sections each numbered consecutively from the first section of the first leaf through all the first sections and then through all the second sections to the 20 second section of the last leaf, said sections to be superposed one upon the other when separated so that the numbers will come in consecutive order, substantially as described.

Signed at New York, in the county of New 25 York and State of New York, this 25th day of May, A. D. 1899.

FREDERICK M. TURCK.
